Attorney.

UNITED STATES PATENT OFFICE.

HUBERT VALENTIN NEUKIRCH, OF ZWICKAU, GERMANY, ASSIGNOR TO ERNST EMIL FREYTAG, OF ZWICKAU, GERMANY.

ACETYLENE-GAS GENERATOR.

No. 866,955.

Specification of Letters Patent.

Patented Sept. 24, 1907.

Application filed December 26, 1906. Serial No. 349,558.

To all whom it may concern:

Be it known that I, HUBERT VALENTIN NEUKIRCH, a subject of the Emperor of Germany, and a resident of Zwickau, Saxony, Germany, have invented a certain 5 new and useful Improvement in Acetylene-Gas Generators, of which the following is a specification.

This invention relates to an acetylene gas generator constructed on the drip system wherein the excess gas evolved is led from the gas holder to an auxiliary 10 burner to be consumed there.

The novel feature of the present construction consists in the connection of the auxiliary burner tube with the upper part of the water container so that said tube has a double function, being used as air supply tube to the 15 water container at normal gas pressure (dynamic pressure) and at the auxiliary burner tube for leading off and consuming the excess gas with increased gas pressure. In known apparatus with a water seal fitted into the auxiliary burner tube such a double function is im- 20 possible.

In the accompanying drawings, Figure 1 is a vertical section of a generator embodying my invention, and Fig. 2 is a cross section through the main chamber and through the main and supplementary burners of Fig. 1.

25 As shown, the carbide holder *a* and the water container *b* are connected to one another, gas tight, at *c*. The water container *b* is provided with a filling orifice *d* which is closed gas tight while the burner is in use. From the carbide holder *a* a tube is led direct to the main 30 burner tube *h*¹. The water container is always in communication with the atmosphere through the auxiliary burner tube *h*² (separate from *h*¹) and the pipe *g* closed by a perforated cover or sieve *g*¹. On the other hand it is connected with the carbide holder by the 35 drip pipe *e* having the openings *x* and the pipe *i* the top of which is closed by a perforated cover or sieve *i*¹, and with a bottom plate having perforations *y* therein. With normal evolution of gas, the gas is consumed by the burner *h*¹ while the air passes through the auxiliary 40 burner *h*² and the pipe *g* to the water level in the water container *b*, so that the drip apparatus releases a number of drops per second corresponding to adjustment of the valve *e*¹, which is provided with a hand piece *e*² and an upper threaded end *e*³. In consequence of the 45 slight vacuum produced in the water-container by the combustion of gas in the main burner, air is caused to stream into the apparatus through the tube *h*².

With increase of gas pressure when the main burner *h*¹ can no longer consume the gas evolved the excess gas flows through the pipe *i* which is closed by sieves to 50 the pipe *g* and to the auxiliary burner *h*², where, being ignited from the main burner, it is consumed.

So long as gas is produced it will follow the path of least resistance, that is through the burner tube *h*¹ to the main burner. In no case will the gas pass through 55 the tubes *i* and *g* closed by sieves on its way to the main burner at normal pressure, since the sieves offer considerable resistance to the gas. Owing to the flow of the gas through the tube *h*¹ to the tube *i* in normal production of gas a suction action is exerted so that in fact 60 with normal production of gas air enters through the auxiliary burner tube *h*² and through the tube *g*, which air presses on the water level in the holder *b*. Should any air pass through the tube *i* into the gas holder itself, there would be no risk of explosion, for gas mixed with 65 air would only explode when the flame is open. The present lamp is however completely closed so that no flame can pass into the interior of the lamp and a mixture of air and gas in the interior of the lamp would do no harm. 70

The sieves *i*¹ and *g*¹ are simply sieves having very fine perforations which permit the passage of gas only, and prevent, in case the lamp is upset, the water passing to the carbide holder or outwardly through the auxiliary burner pipe. Owing to the adhesion of liquid 75 to the sides of the perforations in said sieves, no water can pass through said sieves.

Having now described my invention, what I claim and desire to secure by Letters Patent of the United States is:

The improved acetylene gas generator, comprising the combination, with a water container, a carbide holder beneath said water container, a drip pipe passing from the water container into the carbide holder, a main burner connected with said carbide holder, and an auxiliary burner, of an auxiliary burner pipe connecting the auxiliary burner with the water container, a sieve closing said auxiliary burner pipe, a pipe connecting the water container with the carbide holder, and sieves closing said last mentioned pipe, substantially as described. 80

In testimony whereof I have signed my name to this specification in the presence of two subscribing witnesses.

HUBERT VALENTIN NEUKIRCH.
